CLAIM

The ornamental design for chaps, as shown and described.

DESCRIPTION

FIG. 1 is a front perspective view of chaps showing my new design;

FIG. 2 is a rear perspective view thereof; and,
FIG. 3 is a right side elevational view thereof; the left
side being a mirror image.

The broken lines shown throughout the views are un-
derstood to represent conventional stitching.

FIG. 3

FIG. 2

FIG. 1
